UNITED STATES PATENT OFFICE

2,256,534

MASSAGING DEVICE

Alex S. Tjaden, Edna, Tex.

Application February 26, 1940, Serial No. 320,745

1 Claim. (Cl. 128—63)

This invention relates to new and useful improvements in a massaging device.

An object of this invention is to provide a new and improved massaging device wherein the patient is cradled so that the massaging is done beneath the patient when the patient is in a relaxed position.

An important object of the invention is to provide an improved massaging device wherein the massaging is done beneath the patient while the patient is in a relaxed position and the stroke of the massaging element may be quickly and easily changed and varied.

A further object of the invention is to provide an improved device for vibrating and massaging the body while it is in a reclining or relaxed position, said massaging being accomplished by a cradle which is suspended from points above the patient.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a view in elevation of a massaging device constructed in accordance with the invention.

Figure 2 is a plan view of said device.

Figure 3 is an enlarged sectional view of the supporting bearing for the crank arm,

Figure 4 is an enlarged view, partly in section and partly in elevation, of the adjusting arm constructed in accordance with the invention,

Figure 5 is an enlarged, horizontal, cross-sectional view taken on the line 5—5 of Figure 4, and

Figure 6 is an enlarged, horizontal, cross-sectional view taken on the line 6—6 of Figure 3.

In the drawing, the numeral 10 designates an upstanding frame. Said frame is provided with a plurality of legs 11, having rollers 12 on their lower ends whereby said frame may be easily moved about. The frame is substantially rectangular in cross-section, and has a raised or offset platform 13 provided on its top. It is pointed out that said platform is terminated short of one of the longitudinal edges of said frame. A motor 14 is suitably mounted on the platform 13, and is provided with a pulley 15 mounted upon one end of the shaft 15' of said motor. An elongated shaft 16 is mounted transversely of the frame at one side of said motor,

and is suitably held to said platform by a plurality of upstanding bearing blocks 17. A pulley 18 is mounted on said shaft and in alinement with the pulley 15 of the motor 14. A suitable belt 19, or any other suitable means, connects the two pulleys so that said shaft 16 may be rotated by said motor.

A circular eccentric disk 20 is mounted upon one end of the shaft 16. Said disk is securely attached to the shaft 16. The disk 20 is provided with an elongated, diametrical, dovetail groove 21. It is pointed out that in the drawing, said groove has been shown as disposed diametrically of said disk. However, any suitable arrangement of said groove may be used. A bolt 22 has its head 23 formed square and dovetailed so as to have a sliding fit within the groove 21. The bolt projects laterally from the disk so as to form a crank arm. The outer end of the shank 25 of the bolt 22 is provided with external screw threads 24.

An elongated arm 26 is pivotably mounted on the top of the frame below the platform 13, but adjacent to the disk 20. A pivot pin 27 is provided in the central portion of said arm, and is supported by a pair of bearing blocks 28 so that the ends of said arm are free to swing in a vertical arc. The outer portion of one end of the arm is enlarged at 29 to form a crosshead, said crosshead being provided with an elongated reduced portion 30. It is pointed out that said reduced portion extends longitudinally of the enlarged portion 29 of the arm. Lugs 31 extend upwardly above the reduced portion at each end thereof, thereby providing stops at each end of the reduced portion. Said lugs have their upper surfaces formed in a horizontal plane and are provided with internally screw-threaded, vertical openings 32. The bottom 40 of the reduced portion 30 is provided with a longitudinal groove 33. A block 34 covers the reduced portion 30, and is attached to said crosshead by bolts 35 which engage the screw-threaded openings 32. The block 34 has its central portion 36 reduced so as to mate with the reduced portion 30. The reduced portion 36 is provided with a longitudinal groove 37 in vertical alinement with the groove 33. Thus the reduced portions 30 and 36 form an elongated 45 opening 38 in the crosshead.

A bearing block 39 has a sliding fit within the opening 38; said block being provided with tongues 40 on opposite sides thereof, which ride within the grooves 33 and 37, thus allowing said block to slide within the opening 38, but posi-

tively holding said block within said opening. A central, circular, transverse opening 41 is provided in said bearing block, and receives the shank 25 of the crank arm 22 provided on the eccentric disk 20. Surrounding the shank 25, is a sleeve 42 which has one end abutting the face of the disk 20 and its outer end substantially flush with the outer surface of the block 39. A roller bearing 43 surrounds the sleeve 42, and is confined between said sleeve and the walls of the opening 41. The inner end or head 23 of the crank arm 22 is connected to the disk 20, as stated hereinbefore. A suitable nut 43' engages the screw threads 24 to secure the bolt or crank arm 22 and disk 20 to the bearing block 39 and the arm 26. A link 44 is connected to each end of the arm 26 and pivotably depends from said arm. A belt 45 has each of its ends connected to one of said links, and hangs loosely therefrom, thereby forming a cradle so that a patient may lie upon a table or other suitable support 46, and the belt 45 will underlie said patient. As may readily be seen in the drawing, the frame 10 straddles said table and may be moved upwardly and downwardly over the table, so that different portions of the patient's body may be massaged. A control (not shown) for operating the device may be placed on top of the device or under the same, so that a person may give himself a treatment. It is pointed out that a cover (not shown) may be placed over the motor or over the entire upper portion of said device. The cradle formed by the belt 45 is an important feature of this invention. The belt may be formed with any width desirable. A belt approximately sixteen inches wide has been found to be very satisfactory, since it is sufficiently wide to cover a majority of the large surfaces of a patient's body. However, it is repeated, that any desirable width belt may be utilized to advantage.

In the operation, the motor 14 is started, thereby rotating the pulley 18 and the shaft 16 through the medium of the belt 19. The disk 20, which is connected to the outer end of said shaft, will also be rotated. The operator moves the crank arm 22 along the dovetailed groove 21 so as to obtain the desired stroke upon the cradle 45. In other words, if the crank arm is placed near the center of the disk 20, it will produce a fast vibrating stroke of small amplitude. However, if the same is placed at either end of the groove, the device will produce a long, or large amplitude, vibrating stroke.

As the crank arm is carried around with the

disk in an eccentric motion, and the bearings 41, it will rotate within the bearing block 39, thereby causing the block to move in a similar eccentric motion. The tongues 40 of said bearing block will ride within the grooves 31 and 31' of the crosshead 29 as the block moves back and forth in the opening 38. Thus the tongues 40 keep said bearing block in alignment at all times by allowing the same to slide within the opening 38. It is pointed out that when the crank arm has been placed so as to produce the desired stroke, the nut 43', provided on the outer end of the shank 25 of the crank arm, is tightened, so that the sleeve 42 will bear against the surface of the disk 20 and the under side of said nut. Thus, as said nut is screwed upon said shank, it will pull the enlarged head 23 up against the inclined surfaces of the groove, and securely tighten and hold said crank arm in the position desired by the operator.

As the disk 20 rotates and moves the crosshead 29 upwardly and downwardly with said rotation, the other end of the arm 26 will be correspondingly actuated, thus producing a rocking movement which will be transmitted through the belt 45 to the patient who will be lying within the cradle formed by said belt. It is pointed out that various changes may be made so as to make said unit more compact, thus producing an efficient and compact unit and administering a massaging treatment to a patient who will be lying within the cradle formed by the belt 45.

Various changes, alterations and modifications may be made in the size, shape and arrangement of the herein described elements, within the scope of the appended claim.

What I claim and desire to secure by Letters Patent is:

In a portable massaging device, the combination of an elevated platform, legs supporting said platform, an elongate arm pivoted intermediate its ends on the platform, a bearing connection at one end of the arm having an elongate opening, a bearing block mounted to slide in the opening of the connection, a disk journaled on the platform and having a dovetail groove extending diametrically across one side, a bolt adjustably confined in the groove of the disk and fastened therein, the bolt being pivotally connected to the sliding block, links each pivoted at one end to opposite ends of the arm, and a massaging belt pivoted at its ends to the links, whereby it hangs in a loop.

ALEX S. TJADEN.
